DESIGN FOR A CLOCK CASE

Frank W. Green, Framingham, Mass., assignor to Warren Telechron Company, a corporation
of Maine

Application October 6, 1937, Serial No. 72,025

Term of patent 14 years

To all whom it may concern:

Be it known that I, Frank W. Green, a citizen of the United States, residing in Framingham, county of Middlesex, State of Massachusetts,
have invented a new, original, and ornamental Design for a Clock Case, of which the following is a specification, reference being had to the accompanying drawing, forming a part thereof.

The figure is a front perspective view of a clock
case showing my new design.

I claim:

The ornamental design for a clock case as shown.

FRANK W. GREEN.
